UNITED STATES PATENT OFFICE.

LOUIS B. PRAHAR, OF NEW YORK, N. Y.

FRAME FOR POCKET-BOOKS, SATCHELS, &c.

SPECIFICATION forming part of Letters Patent No. 365,200, dated June 21, 1887.

Application filed May 10, 1887, Serial No. 237,757. (No model.)

To all whom it may concern:

Be it known that I, LOUIS B. PRAHAR, of the city, county, and State of New York, have invented a new and Improved Frame for Satchels, Pocket-Books, &c., of which the following is a full, clear, and exact description.

Reference is to be had to the accompanying drawings, forming a part of this specification, in which similar letters of reference indicate corresponding parts in all the figures.

Figure 1 is a side elevation of my new frame applied to a pocket-book or purse. Fig. 2 is a front elevation of the frame partially open and with the locking-knobs removed; and Fig. 15 3 is a detailed sectional elevation taken on the line xx of Fig. 1.

The invention will first be described in connection with the drawings, and then pointed out in the claims.

20 A B represent the two jaws or members of the complete frame, each made from a single piece of metal stamped upon a die to form a right angle in transverse section, as shown in Fig. 3, and a continuous curve, as shown in Figs. 1 and 2. These are hinged together at their ends by the pins a a , and one end, a' , of the jaw A is placed outside of the end b' of the jaw B, while the opposite end, a'' , of the jaw A is placed inside of the end b' of the jaw B. 25 A flange, c , is formed upon the inner edge of the jaw A, to overlap the adjacent portion of the jaw B when the frame is closed, and a flange, d , is formed upon the inner edge of the jaw B, to overlap the adjacent portion of the jaw A, so that when the frame is closed one-half of each jaw forms the outer surface or 30 edge of the entire frame. In this manner there can be no opening between the jaws, even

though the rivets a become worn and comparatively loose. The locking studs or bolts F F are secured at the angles i i of the flanges c d , and the portions c' d' , which are overlapped by the flanges c d , are made narrow, as shown clearly in Fig. 2.

By constructing the frame as described the same is cheap and practical and the jaws brace and protect each other; also, the mutual overlapping of the jaws prevents the opening of the jaws when the rivets a and locking-knobs F become loose in the use of the bag, satchel, or purse.

The body D of the bag or purse may be secured to the frame by rivets e e in the usual manner.

Having thus described my invention, what I claim as new, and desire to secure by Letters Patent, is—

1. As a new and improved article of manufacture, a satchel, purse, or pocket-book frame composed of the jaws A B, each struck from a single piece of sheet metal, with a narrow portion at one half thereof and a flange at the other half made flush or on the same curve with the narrow portion of the jaw, substantially as shown and described. 65

2. The jaw A, formed with the flange c to overlap the jaw B, and the said jaw B formed with the flange d to overlap the jaw A, one end of the jaw A being pivoted to the outer surface of the jaw B, the opposite end of jaw A being pivoted to the inner surface of the jaw B, substantially as shown and described. 70

LOUIS B. PRAHAR.
